UNITED STATES PATENT OFFICE.

WINTFORD P. CUNNINGHAM, OF TULSA, OKLAHOMA.

SAFETY HOOK.

Application filed October 27, 1924. Serial No. 746,119.

To all whom it may concern:

Be it known that I, WINTFORD P. CUNNINGHAM, a citizen of the United States, residing at Tulsa, in the county of Tulsa and State of Oklahoma, have invented certain new and useful Improvements in Safety Hooks, of which the following is a specification.

My invention relates generally to oil well apparatus, and in particular to implements used in hoisting well rods, tubing and casing.

Objects of the invention are: to provide a hook for hoisting engagement with elevators attached to rods, tubing or casing, having weight operated automatic hook latching means; to provide a hook of this character equipped with manually operated grip controlled latch releasing means; and to provide a hook of this character so constructed and formed that the latch and release mechanism are protected against accidental operation through fouling of well rigging.

With these objects in view, and such others as will be apparent from the description, the invention resides in the novel construction, combination and arrangement of parts hereinafter described and claimed, and illustrated in the accompanying drawings, wherein:

Figure 1 is a vertical section through a hook constructed in accordance with the principles of the invention, with certain parts of the mechanism in elevation;

Figure 2, a horizontal section on line 2—2 of Fig. 1;

Figure 3, a vertical section on line 3—3 of Fig. 2;

Figure 4, a vertical section on line 4—4 of Fig. 3;

Figure 5, a horizontal section on line 5—5 of Fig. 1.

In the preferred embodiment of the invention, as shown, the hook is constructed of a casting 10 provided at its upper end with a swiveled link 11 for engagement with a hoisting cable in the usual manner. At its lower end the casting is formed to provide a hook 12, internally slotted to receive therein in nested relation a trigger member 13 when the hook is latched.

The tip 14 of hook 12 is offset from the body of the casting which between the hook and its connection with the link 11, is formed

of spaced side walls 15 and 16 connected throughout their length by a cross web 17. Adjacent the web 17 the body of the casting is formed with an offset hand grip portion 18 channeled to receive in slidable nesting relation a movable supplemental grip member 19 carrying intermediate its ends a rigid bolt 20 slidably disposed through the web 17 for a purpose herein-after explained. A coil expansion spring 60 having one end retained in a socket formed for the purpose in the supplemental grip 19 and the other end bearing against the inner face of the grip 18, acts normally to force the bolt in projected position through 70 web 17.

The body of the trigger 13 is shaped to conform to the contour of hook 12, and is provided with an integrally formed upper shank 22 at its inner end, which shank is reduced in cross-section and is enlarged laterally at its upper end into the head 23. The entire trigger unit comprising trigger 13, shank 22 and head 23 is 80 slidable vertically within the casting between the side walls 15 and 16, being normally drawn upwardly into the position illustrated in Figure 3 by means of a coil contraction spring 24 connected between a lug 25 formed in the casting at the end of the 85 spring recess socket 26, and a reduced web 27 on the trigger unit head 23. An integral stop lug 28 on the upper edge of head 23 serves to limit the upward movement of the 90 unit. Beneath the head 23, the walls of the casting are connected by a transverse pin 29, which in conjunction with the web 17, forms a guide for the trigger shank 22.

Adjacent its upper edge, the head 23 of the trigger unit is provided with a keeper 95 socket 30, which, when the trigger is in lowered position, receives the spring projected bolt 20 of the supplemental grip member 19, effectively holding the trigger unit in set position against action of the 100 spring 24.

The latch mechanism for the hook comprises a bifurcated latch member having a terminal web 31 and side arms 32 and 33 which straddle the shank 22 and head 23 of the trigger unit between the sides of the shank and head and the walls of the casting, with the terminal 31 disposed to engage the hook tip 14 in abutting relation when the latch is functioning. The inner ends of the 110

arms 32 and 33 are journaled on a pivot pin 34 secured in the sides of a cut away portion in the web 17, so that the latch member is pivoted for vertical rocking movement in

5 the casting. Operating connection between the trigger unit and latch member is secured by means of a connector pin 35 disposed through the respective members and side walls of the casting, the arms 32 and 33 10 being provided with longitudinal slots 36, and the casting walls with vertical slots 37, to permit necessary play of the pin therein.

Hooks constructed in accordance with the principles of this invention, are designed as 15 safety hooks, wherein when in service the hook is latched to prevent any possibility of disengagement of the hook and an elevator. In normal unlatched position, the elements of the device assume the position shown in 20 Figure 3, with the latch 31 open and the trigger 18 in raised position above the hook 12. The stop lug 28 of the trigger unit head 23, is of a height to assure that the body of trigger 13 will not rise above the sides of 25 the hook 12. In operation, the handle 18 is grasped and the hook swung into engagement with an elevator link which rests on the trigger 13. When the hook is lifted the weight of the elevator and attached objects 30 pulls down the trigger against action of the spring 24, and by reason of the connection between the trigger unit head and the side arms of the latch member, as the trigger is lowered the latch 31 will descend to bear 35 against the hook tip 14 in the position shown in Figure 1. As the keeper socket of the trigger unit head comes into alignment with the bolt 20, the action of spring 21 will 40 project the bolt into the socket, effectively locking the hook in closed position. When it is desired to release the hook, the operator tightens the grip upon the supplemental grip member 19, drawing it against the action of spring 21 to retract bolt 20. On 45 release of the trigger head by retraction of the bolt, the trigger unit will be raised, or will tend to raise, under action of the spring 24. The hook is manipulated to relieve pressure on the trigger, whereupon the latch will 50 rise to open position shown in Figure 3 permitting release of the hook.

By reason of the offset relation of the handle grip 18, a guard is provided for the supplemental grip 19 constituting the latch 55 release mechanism, so that any possibility of the latch release becoming fouled in the well rigging is eliminated. Additionally to effect this object, the casting is rounded off to provide a surface that will not become caught 60 in the rigging.

While I have illustrated and described certain details of construction in this preferred form of the hook, it is to be understood 65 that the invention is not limited thereby, but that any desired modifications

and changes may be made in the structural details thereof as will fall within the scope of the invention, as claimed.

I claim:—

1. A safety hook comprising a hook member, a latch for said hook member, and means for throwing said latch over said hook member by the weight of the member engaged. 70

2. A safety hook comprising a hook member, a latch for said hook member, means for operating said latch, by the weight of the member engaged, and manually operated latch release means carried by said hook. 75

3. A safety hook comprising a hook member, a latch for closing said hook member, a trigger in said hook for throwing said latch, upon engagement by a member to be lifted, means for locking said latch in closed position, and handle grip means for releasing 80 said latch. 85

4. A safety hook comprising a hook member, a weight operated trigger disposed within the curve of said hook member, a hook latch controlled by said trigger, automatic latch locking means in said hook, and manually operated means on said hook for releasing said latch. 90

5. A safety hook comprising a casting formed in a hook at one end, a weight operated trigger disposed within said hook and slidably in said casting, a pivoted latch in said casting controlled by said trigger to close said hook, an automatic latch lock in said casting, a handle grip on said casting, and means in said grip for releasing said latch lock. 95 100

6. A safety hook comprising a casting formed in a hook at one end, said hook having a recess therein, a weight operated trigger in said recess, a hook latch pivoted in said casting, a head formed on said trigger and in connection with said latch, an automatically operable locking bolt in said casting for engagement with said trigger head 105 to lock said latch in closed position, a handle grip formed on said casting, and manually operable locking bolt release means in said grip. 110

7. A safety hook comprising a casting, a slotted hook formed in said casting, a handle grip formed on said casting, a weight operated trigger slidably disposed in the slotted portion of said hook, a shank on said trigger and a head on said shank 120 slidably within said casting, a latch for said hook pivoted in said casting, operating connection between said latch and trigger head, a spring projected trigger locking bolt for automatically locking said trigger and latch in closed position, and means in said handle grip for releasing said trigger locking bolt. 125

8. A safety hook comprising a casting, a slotted hook formed in said casting, a 130

- handle grip formed on said casting, a weight operated trigger slidably disposed in the slotted portion of said hook, a shank extending from said trigger, a lateral enlarged head on said shank above said trigger and provided with a bolt keeper recess, a latch for closing said hook, arms on said latch straddling said head and pivoted at one end to said casting, operating connection between said arms and trigger head, a locking bolt in said casting for engaging the keeper recess in said head to lock said head and latch in closed latch position, spring projection means for said bolt in said handle grip, and a supplemental handle grip associated with said locking bolt for release thereof.
9. A safety hook comprising a hook member, a latch, means for automatically closing and locking said latch upon engagement 20 by the hook with a member to be lifted, and means for automatically returning the latch to open position.
10. A safety hook comprising a hook member, a latch, means for automatically 25 moving said latch to operative and inoperative positions, and means for automatically locking said latch in operative position.
11. A safety hook comprising a hook member, a latch, means for automatically 30 moving said latch to operative and inoperative positions, means for automatically locking said latch in operative position, and manually operable release means for said locking means.

In testimony whereof I affix my signature.

WINTFORD P. CUNNINGHAM.
